James L. Morris

Attorney

UNITED STATES PATENT OFFICE.

ERNEST O. ATWOOD, OF BOISE, IDAHO, ASSIGNOR, BY MESNE ASSIGNMENTS, OF ONE-HALF TO ATWOOD GAS SAVER COMPANY, A CORPORATION OF IDAHO, AND ONE-HALF TO J. W. MEHARGUE, BOTH OF BOISE, IDAHO.

INTERNAL-COMBUSTION ENGINE.

Application filed June 26, 1922. Serial No. 571,002.

To all whom it may concern:

Be it known that I, ERNEST O. ATWOOD, a citizen of the United States, residing at Boise, in the county of Ada and State of Idaho, have invented new and useful Improvements in Internal-Combustion Engines, of which the following is a specification.

This invention relates to internal combustion engines and particularly to means for admitting auxiliary air to the combustible mixture conduit at a point between the mixing chamber and the carbureter and the cylinders of the engine.

15 The present invention is a modification of the device described and claimed in my companion application No. 493038, filed August 17, 1921, which embodies a gasket having a serrated gas aperture, and inserted 20 between the flanges of the carbureter and intake manifold and provided with an air check valve, the particular invention covered in said application being the means and method of constructing a gasket as aforementioned, and involving novel features of stamping the gasket and affixing the check valve thereto.

In the present invention it is contemplated 30 that the same structural features may be applied to the flanges themselves of the carbureter or manifold, thereby not only extending the application of the invention to a variety of devices, but also attaining a new function for the apparatus which is not appreciably performed by the modification 35 embraced in said gasket, namely the heating of the auxiliary air by contact with the walls of the long bore or channel extending through the mass of one of said flanges and 40 in which the air check valve is confined.

The present invention, then, has for its object the provision of means for admitting air to the mixture conduit of an internal combustion engine through a bore or channel 45 extending through the flange of one of the flanged elements of said conduit from the peripheral edge thereof to the central gas aperture, the latter being serrated, with the same objects in view as attend the similar construction described in said companion case.

For the attainment of these ends and the accomplishment of other new and useful objects, as will appear, the invention consists

in the features of novelty in the construction, combination and arrangement of the several parts generally shown in the accompanying drawings, described in the specification, but more particularly pointed out in the appended claims. 55

In the drawings accompanying and forming a part of this specification, and wherein the preferred embodiment of my invention is illustrated:—

Figure 1 is a perspective view of a carbureter showing the auxiliary air valve and the serrated gas aperture constructed in the flanged portion thereof. 65

Figure 2 is an end view of said flanged portion showing the auxiliary air valve in section. 70

Figure 3 is a detail view of the flange of the carbureter showing the auxiliary air valve applied thereto in a slightly different manner from that illustrated in Figure 1. 75

Figure 4 is a perspective view, in side elevation, of an intake manifold showing a flange construction similar to that of Figure 1.

Figure 5 is a detail view of the lower end 80 of the intake manifold showing the exhaust valve applied thereto in a manner similar to that illustrated in Figure 3.

Referring now in detail to the several figures, the numeral 1 represents the casing 85 of the float chamber of a carbureter, which communicates with a mixing chamber 2 having an air intake 3 which is shown as connected to the hot air stove 4 overlying the exhaust pipe 5. By this means heated air 90 is drawn into the mixing chamber of the carbureter past the lower end of the needle valve 6, in a manner which is well understood and needs no further description. The outlet end of the mixing chamber is provided with a vertical flange 7 which is adapted to be placed in abutment with the flange 8 of the intake manifold 9 shown in Figure 4, a gasket, not shown, intervening, and said flanges being bolted tightly together in clamping relation to said gasket by means of bolts passing through the aligned apertures 10. 95

In my companion application I have provided the gasket which is interposed between these flanges when the mixture conduit is in assembled relation with an auxiliary air valve. In the present invention I 100

have provided the flanges themselves with the auxiliary air valve. I have also included in the flange construction the serrated gas passage which is described in my said companion application and also in application No. 493,038, filed August 17, 1921.

To this end, and referring first to the form of construction shown in Figures 1 and 4, I have cast the flange of the carburetor with a central opening having serrated walls 11, said flange being also cast with a depressed channel 12 extending from the central gas passage to the peripheral edge of said flange. Within this channel is seated the auxiliary air valve 13 which is originally of tubular formation, the lower part of which is seated in said channel and then flattened by pressure to conform to the shape of said channel and to become fitted in tight relationship to the walls thereof. As described in said companion application the act of flattening the lower portion of said tube also serves the purpose of retaining in place the spring 14 and the ball 15, shown in Figure 2 by means of which the air-inlet opening 16 in the end of said tube is controlled. By the disposition of the auxiliary valve in the manner aforesaid the lower or stem portion thereof is in contact with a relatively extensive surface of the flange casting and therefore is subject to a rapid rate of heat interchange through conduction from the metallic mass of said flange. It will be observed that the carburetor obtains its main supply of air from the heated air stove 4 which overlies the exhaust pipe 5, therefore the casting of the carburetor is maintained relatively warm during the operation of the engine, the heat from which, conducted through the mass of the flange to the stem of the auxiliary air valve will warm the current of incoming auxiliary air, maintaining a state of vaporization of the fuel mixture in the manifold and preventing condensation of the fuel constituent out of said mixture at the point where the auxiliary air enters, as would be the case were the auxiliary air admitted in a cold state.

In prior constructions where an auxiliary air valve has been attached to the wall of the gas conduit it has been tapped into said conduit normal to the surface of the walls thereof at a point where the walls are thinnest, affording a metallic contact between the walls and said air valve of small area, being merely the annular ring of contact where said auxiliary air valve passes through the wall of said conduit and providing but a negligible heat-conductive surface.

It is not necessary to the carrying out of the present invention that the stem of the auxiliary air valve be squeezed into the channel in the flange 7 as has been described, but it may be secured to said flange in any other

way, the essential feature being that the auxiliary air shall traverse the lengthy bore in the flange extending from the central gas passage to the peripheral edge of said flange. Another form of attachment for the auxiliary air valve is therefore shown in Figures 3 and 5 in which the valve stem is threaded and engages a threaded bore in the flange 7. In this case it is not essential even that the threaded portion of the valve shall extend throughout the bore in the flange for the purpose of invention is carried out by having the auxiliary air itself traverse the heated passage through said flange.

It is to be understood that the manifold 9, is heated by actual contact with the cylinder walls at connections 17, and by its proximity when assembled to the exhaust manifold not shown, thus permitting the flange 8 to impart heat to the incoming stream of the auxiliary air.

It is within the scope of the invention that various changes may be made in the form and relation of parts to suit different requirements of use, and that the invention, therefore, is not limited to the precise details of construction and arrangement shown.

Having described my invention what I claim as new and desire to secure by Letters Patent, is:—

1. In an internal combustion engine, a fuel mixture conduit, having a portion thereof arranged in heat-receptive relationship to said engine, said portion being constructed with an integral connecting flange surrounding the gas-passage therethrough, the wall of said flange surrounding said gas passage being serrated, a duct formed in said flange extending from the peripheral edge thereof to said gas passage the outer end of said duct communicating with the atmosphere.

2. In an internal combustion engine, a fuel mixture conduit having a portion thereof arranged in heat-receptive relationship to the engine and provided with an integral connecting flange surrounding the gas passage therethrough, the wall of said gas passage through said flange being serrated, said flange being constructed with a channel leading from said gas passage to the peripheral edge of said flange, a tubular member seated in said channel and frictionally engaging the walls thereof, said tubular member being open at its outer end to the atmosphere and provided with an inwardly opening check valve.

In testimony whereof I have hereunto set my hand in presence of two subscribing witnesses.

ERNEST O. ATWOOD.
